UNITED STATES PATENT OFFICE.

BERTRAM H. SAUNDERS, OF PATERSON, NEW JERSEY.

PILING MACHINE.

Application filed March 13, 1920. Serial No. 365,588.

To all whom it may concern:

Be it known that I, BERTRAM H. SAUNDERS, a citizen of the United States, and a resident of Paterson, county of Passaic, and State of New Jersey, have invented a new and useful Improvement in Piling Machines, of which the following is a full, clear, and exact description.

My invention relates to improvements in piling machines, and the general object of my invention is to produce a simple, substantial and inexpensive machine by which wet, or if desired, dry fabrics in long lengths can be conveniently and evenly piled so that the piles can be readily rewound and removed when desired. My invention is intended also to produce a machine of this class in which the length of fabric is piled in and out in a general star shape, and furthermore, to provide means by which the discharge chute which delivers the fabric to the pile can be adjusted so as to give it the desired throw or movement within certain limits, can also start the inner part of the pile at a desired point, and further to hang and arrange the discharge chute so that as it swings in and out in forming the pile, it will be of variable length, thus enabling it to work to better advantage in a vessel such as a kier, as will be hereinafter described.

Another object of my invention is to construct and arrange the feed and piling mechanisms in separate units which can be connected by a detachable feed pipe, so that the feed mechanism may be permanent, and the piling mechanism can be arranged beneath the feed mechanism when desired and connected up by the detachable pipe, as will hereinafter appear. Other advantages and objects of the invention will appear in the description which follows.

Reference is to be had to the accompanying drawings forming a part of this specification, in which similar reference characters indicate corresponding parts in all the views.

Figure 1 is a central vertical section of a machine embodying my invention, the same being shown applied to the mouth of the kier and with parts broken away.

Figure 2 is a broken side elevation of the construction shown in Figure 1, and taken at right angles to Figure 1, and

Figure 3 is a sectional plan on the line 3-3 of Figure 2.

The structure is shown by way of example,

and many of the parts can be changed or altered without affecting the invention. The feed mechanism, particularly, is similar in a general way to what is generally used, though certain details are novel. As illustrated, the feed mechanism is separate from the piling mechanism, and is supported on a framework 10, and comprises in part a stationary feed pipe 11 which is widened at the top, and which merges into a short pipe 12 having a flange 13 by which it can be attached to the framework 10. The pipe 12 also receives several branch pipes 14 which are adapted to supply water or liquid chemicals to assist the feed of fabric 15 through the pipe. It is customary to supply water or liquid chemicals in this way, but the invention is not limited to such an arrangement. The fabric 15 is supplied in long lengths to the pipe 11, and is delivered from a reel 16 carried by a shaft 17 which can be supported and driven in any approved way.

As stated, this feed mechanism is stationary, and the piling mechanism is carried by a frame 18 which is preferably, though not necessarily, parallel angle irons connected by a centre brace 19 and by cross pieces 20 near the ends. The side pieces of the frame are extended as shown at 21 in Figure 1 to form handles by which the frame and the entire piling mechanism carried thereby, can be lifted from a kier 9, and moved or placed thereon as desired, and moved about in any preferred way. When used in connection with a kier, which is the most common use of the invention, the frame can be fastened to the mouth of the kier in any suitable way, and can conveniently be fastened by means of two of the usual circle of swing bolts 22 on the kier, and these can be provided with nuts 23 or the like to engage a part of the frame 18 and hold it in place. The frame carries a fixed stationary pipe 24 which depends from the central part of the frame, and can be rigidly secured in the central member 19, as for instance by screwing it therein, as shown in Figure 1. This pipe 24 forms a continuation of the pipe system by which the fabric to be piled is conducted to the piling mechanism, and is adapted to align with the pipe 11-12 of the feed mechanism, and with a detachable connecting pipe 25 which is adapted at its lower end to be dropped into the socket 26 at the top of the pipe 24, and which at its upper end is prefer-

ably expanded as shown at 27 so that after the frame 18 and the piling mechanism are in place beneath the feed mechanism, the pipe 25 can be pushed up on the pipe 12, and then 5 dropped into its socket 26 so that the fabric will be delivered through the several pipes 11, 12, 25, 24, and the delivery chute 45-48 hereinafter referred to.

Journalized on the pipe 24 is a relatively 10 large gear wheel 28 which forms a rotatable support for the piling mechanism, and which is driven by a worm 29, and this is supported in brackets 30 dropped from the frame 18. The worm can be turned in any 15 suitable manner, as for instance by providing it with a pulley 31 and a driving belt 32 which can connect with a pulley 31^a on the shaft 17.

The gear wheel carries on its upper side 20 tilting frames 33-33^a which are generally U shaped. These are arranged opposite each other and on opposite sides of the axis of the wheel 28, as shown clearly in Figure 3, and the frame 33 is pivotally supported on studs 25 34 projecting from the hub of the gear wheel, while the frame ends 33^b project inward beyond the pivot as shown clearly in Figure 3 and carry the opposite frame 33^a. It is desirable to raise and lower the frame 30 ends 33^b of the frame 33, and to this end the back of the frame is provided with an arm 35 which engages a reduced part 36 of a bolt 37 (see Figure 1) which is threaded into a boss 39 on one of the spokes of the wheel 28, 35 and is provided with a hand wheel 40 or similar means for turning it. Thus by turning the hand-wheel, the bolt 37 can be screwed in or out, and the inner ends 33^b of the frame 33 raised or lowered as desired. 40 The object of this will be particularly explained below.

The inner end portions of the frame 33^a are pivotally supported as shown at 41 on the ends 33^b of the frame 33, and the inner 45 ends of the frame 33^a merge into depending hangers 42 so that the frame 33^a is substantially a bell crank. These hangers terminate at their lower ends in hooks 43 which engage and support the studs 44 on the upper 50 end 45 of a swinging delivery chute, the member 45 having preferably a widened mouth 46 which comes below the reduced end 47 of the pipe 24 above referred to. The lower end 48 of the distributing chute 55 slides or telescopes on the member 45, and is pivotally connected by means of the link 49 with a stud 50 which is secured to the under side of the boss 39 (see Figure 1) and can be conveniently screwed into the boss. 60 Thus it will be seen that as the telescoping chute 45-48 swings in and out owing to the different centres of the upper end of the link 49 and the support of the chute, the outer member 48 will slide back and forth 65 on the inner member 45, and as the chute

swings upward it will be elongated as shown by dotted lines in Figure 1. This enables the chute to work to better advantage in a vessel or kier, or in fact under almost any circumstances, as the fabric can be piled 70 higher by it than it otherwise could be because where a long chute is used and it does not telescope, it will obviously be interfered with by the centre of the pile as the top of the latter approaches the range of the chute. 75

The chute is tilted by means of an arm 51 which is secured to the member 45 at the upper edge and on one side, and this arm rides on the lower edge 52 of a cam 53 which is suspended from the under side of the gear 28 80 and is preferably journaled on a stud 54 which is fastened to the gear as shown in Figure 1. To the hub of the cam 53 is secured a pinion 55 which meshes with a fixed gear 56 this being fast on the lower end of the pipe 24. 85

Attention is called to the fact that the teeth in the fixed gear are not a multiple of the teeth in the pinion the object of the odd tooth in the pinion being to create as large a 90 cycle of distribution in the kier as possible.

It will be noticed that as the fabric passes down through the feed pipes and distributing chute, the whole piling mechanism will rotate with the gear wheel 28, and the distributing chute will be swung in and out so as to distribute the fabric in a general star shape and pile it up beneath the piling mechanism, whether this be in a kier or bin or open space. 95

The hanger arms 42 can be adjusted in and out with relation to the cam 53 in a manner similar to that already described for adjusting the frame 33, that is to say, the frame 33^a has on its back side an arm 35^a which is adjusted by a bolt 37^a and hand-wheel 40^a in the same way that the frame 33 is adjusted by the bolt 37. 100

Obviously the particular means of adjusting the discharge chute can be varied without affecting the invention, but I have shown a simple and efficient means of doing it. It will be seen that by adjusting the frame 33 the point of suspension of the discharge chute can be raised or lowered, and consequently the inward and outward limit of the throw of the chute thereby regulated, so that the inward starting point of the chute can be made the centre of the kier, or any point (within the limits of the adjusting device) 110 outside the centre, whichever position in the judgment of the operator best distributes the goods, and by moving the back of the frame 33^a up or down, the crank arms 42 can be thrown in and out with reference to the cam 53, and so the sector through which the discharge chute 45-48 will swing can be made greater or less, according as the weight of the goods, referring to the number of yards to a pound of cloth, being piled shall neces- 115 120 125 130

sitate and the cloth not be piled too densely at the centre, nor delivered beyond the periphery of the kier, which causes too rapid building of the pile at that point.

5 When the machine is in operation it will be seen that the worm wheel 29 will rotate the gear 28 thereby carrying with it the entire piling mechanism including the frames 33 and 33^a, the discharge chute 45-48, and the cam 53. Thus the main gear 28 serves as a carrier and driver of the piling mechanism. As the cam 53 is carried around with the gear 28, its pinion 55 meshes with the fixed gear 56 so that the cam is rotated, and 15 acting on the arm, it swings the discharge chute 45-48 in and out and as the latter is travelling in a circular path, the fabric will be piled in a general star shape and in even layers without undue twisting or tangling, 20 so that it can be unpiled readily when desired. It will be noticed that the gear wheel 28 is very much larger than the worm wheel 29 which it engages, and therefore the wheel 28 will turn very slowly, carrying the piling 25 mechanism with it. Thus it is a very simple matter to adjust the piling mechanism so as to regulate the position of the chute at the beginning of its throw, and to regulate its throw by means of the hand wheels 40 and 30 40^a, as already described. The operator simply takes hold of the hand wheel desired and turns it slowly, the slow movement of the gear wheel 28 easily permitting this. This is an important matter, as with other 35 piling machines having such regulation, it is necessary to stop the machine to effect the desired adjustment.

It will be understood, of course, that the frame 18 can be supported in other ways than on the top of the kier, in case the piling is to be done in some other form of vessel or on the floor, and it will be noticed that the piling mechanism is entirely separate from the feeding device, and can be readily connected and disconnected, thus making the machine convenient for shop use. Moreover, the construction of the frame 18 makes it very easy to move the frame about.

The details of construction can in many 50 instances be changed without affecting the invention, the important features of which are to have the detachable arrangement between the feed and piling mechanism, to provide means for shortening and elongating 55 of the delivery or discharge chute, and to provide a frame which is easily portable for carrying the piling mechanism, to have the main gear serve to rotate and operate the piling mechanism, and to provide means for adjusting the chute both as to its throw and as to the point at which it begins the inner part of the piling.

I claim:—

1. A piling machine comprising a stationary feed mechanism for feeding the fabric,

said feed mechanism being spaced apart above and independent of the piling mechanism, a piling mechanism having means for supporting it below the feed mechanism, and a detachable guide adapted to connect the feed and piling mechanisms to conduct the fabric from one to the other. 70

2. A machine for piling wet fabrics, comprising a feed mechanism, a piling mechanism employing a swinging discharge chute, and a detachable pipe adapted to connect the feed mechanism with the discharge chute. 75

3. A piling machine comprising a relatively permanent feed mechanism, a portable frame carrying the piling mechanism, said mechanism being independent of the feed mechanism and adapted to be spaced apart from and below it, and a detachable connection between the feed and piling 80 mechanisms by which wet fabric can be delivered from the feed mechanism to the piling mechanism. 85

4. A piling machine comprising a relatively permanent feed mechanism, a portable frame carrying a pipe and a feed chute suspended below the pipe, and a detachable pipe adapted to connect the feed mechanism with the pipe carried by the frame. 90

5. A piling machine having a swinging chute to deliver the fabric to a pile, means for delivering fabric to the chute, and means operable while the machine is in motion for positioning the chute at the beginning of its swing. 95

6. In a fabric piler, a chute, means for simultaneously rotating and oscillating said chute, and means operable while the machine is in motion for varying the distance through which said chute is oscillated. 100

7. A piling machine having an extensible chute, means for delivering fabric to be piled to the chute, means for elongating and shortening the chute as it swings in and out, means for swinging the chute, and means for regulating its throw. 110

8. A piling machine having a swinging chute to deliver fabric to a pile, means for moving the chute in a generally circular path, crank arms supporting the chute, a cam mechanism for swinging it, and means for adjusting the crank arms with relation to the cam. 115

9. A piling machine comprising a vertically arranged pipe through which fabric may pass, a gear wheel turning on the pipe, oppositely arranged frames pivotally supported on the gear wheel, the frames being also pivoted together, crank arms carried by one of the frames, means for adjusting the frames, a swinging chute carried by the crank arms, a rotatable cam suspended from the gear wheel, and means for rotating the cam on its own axis. 120

10. A piling machine comprising a verti- 125

cal pipe through which fabric may pass, a gear wheel rotating upon the pipe, a swinging extensible chute suspended from the gear wheel below the pipe, and a link connection between a sliding member of the chute and the gear wheel whereby the chute is shortened and lengthened as it swings.

11. A piling machine comprising a portable frame, a vertical pipe carried by the frame and through which fabric may pass, a gear wheel rotatably mounted on the aforesaid pipe, a chute pivotally suspended from the gear wheel and below the pipe, and a cam mechanism carried by the gear wheel 15 to swing the chute.

12. A piling machine comprising a stationary feed pipe secured to a support, means for feeding fabric through the pipe, a portable frame carrying piling mechanism 20 adapted to be arranged below the stationary pipe and provided with a guide pipe and distributing or discharge chute, and a detachable pipe adapted to connect the pipe of the frame with the stationary pipe of the feed mechanism.

13. A piling mechanism comprising a portable frame having a pipe extending therethrough, a rotatable gear mounted on the said pipe, a swinging discharge chute 30 below the pipe, means for suspending the chute from the gear, a rotatable cam mechanism for actuating the chute, the cam mechanism being also suspended from the gear, and means mounted on the gear for regulating the discharge chute.

14. A piling mechanism comprising a ver-

tically arranged pipe through which fabric may pass, a gear wheel turning on the pipe, oppositely arranged frames pivotally supported on the gear wheel, the frames being 40 also pivoted together, crank arms carried by one of the frames, a swinging chute carried by the crank arms, a rotatable cam suspended from the gear wheel and arranged to actuate the swinging chute, and independent means for adjusting the aforesaid frames and thereby regulating the chute.

15. A piling machine comprising a stationary feed mechanism, a portable frame 50 carrying piling mechanism, said frame having handle portions at its opposite ends, and a detachable pipe adapted to connect the piling mechanism with the aforesaid stationary pipe.

16. A piling machine comprising a frame, a pipe supported in the frame, a rotatable gear journaled on the pipe, a stationary gear on the pipe, a swinging discharge chute arranged below the pipe, a 60 pinion journaled on the main gear and meshing with the stationary gear, a cam turning with the pinion, and an arm on the discharge chute riding on the cam.

17. In a fabric piler, a chute, means for simultaneously rotating and oscillating said chute and means for varying the distance through which said chute is oscillated.
